UNITED STATES PATENT OFFICE.

EZRA RIPLEY, OF TROY, NEW YORK.

IMPROVEMENT IN CASTING METALS.

Specification forming part of Letters Patent No. 14,115, dated January 15, 1856.

To all whom it may concern:

Be it known that I, EZRA RIPLEY, of Troy, in the county of Rensselaer and State of New York, have invented a certain new and useful Improvement in Casting Metals into the Various Shapes Required for Use; and I do hereby declare that the following is a full, clear, and exact description of the construction and operation of my improved molds; reference being had to the annexed drawings, making a part of this specification, in which—

Figure 1 is a plan view of the mold with cap removed; Fig. 2, a sectional elevation of mold and expanding chamber; and Fig. 3 is a detached view of the ventilated partition.

The same letters refer to like parts in each of the figures.

My invention relates to so improving the art of casting metals by the force of atmospheric pressure that small metallic articles can be cast with sharp edges, points, or lines at less cost than heretofore; and it consists in providing a suitable mold and connecting the interior of an expansive air-tight chamber with the interior of the mold by an air-passage made crevice-like at its place of union with the inside of the mold, and immersing the open mouth of the mold in uncovered melted metal, and then immediately by one impulse of said exhauster instantly removing the air from the mold into the expanded air-chamber through said crevice-like air-passage, so that the melted metal shall be forced into the smallest recesses of the mold before the metal shall congeal, whereby the previous practice of closing the mouth of and extracting the air from the mold before sinking the mouth of the mold into the fluid metal, and the subsequent removal of the stopper from the mouth of the mold, with all the consequent bad effects and loss of time, are avoided, as is also the use of a valve as hitherto employed to prevent the melted metal from rushing into the exhauster at the time of filling the mold.

The description of my improved arrangement for casting metals is as follows, viz: A is a box-mold constructed of cast-iron, soap-stone, plaster-of-paris, or any suitable material. It has an aperture, B, for the admission of fluid metal. This aperture must be sufficiently large to allow the fluid metal to pass in and fill the mold quickly. C is a ventilated

partition formed of a plate or plates of metal or other material, and having vents or air-passages *a a* formed in them for the purpose of communicating with the expanding air-chamber by means of the air-passage and tube F and the recess-passages *b b*, formed in the mold A, or by chamfering or rounding the edges of the partition.

D is a cap or cover for the mold, made to fit into it, and resting upon the ventilated partition. This cap is provided with an aperture, E, through which to pour metal into the mold, if that way is preferred, and in such case the aperture B may be closed; but when the metal is taken in through the aperture B the aperture E in the cover is closed air-tight with fire-clay or with any suitable substance, or is omitted in the cover. The joints between the cover and mold are likewise made perfectly air-tight by luting them with fire-clay or otherwise.

H is an air-passage connecting with the air-tube F, attached to the expanding air-chamber G. This chamber is constructed with two heads or caps, J J, connected with each other by means of an air-tight flexible diaphragm, K. After being compressed, the air-chamber is made to expand by means of a spring, L, arranged inside of the chamber and bearing against the heads to force them apart, thereby expanding the chamber.

The manner of using my improvement in casting metals is as follows: The mold being made air-tight at all places except where the metal is to be taken in, the heads of the expanding-chamber are then pressed together to expel the air from the chamber, when the lower half of the mold is dipped into the molten metal, as represented by the red lines, and at the same instant the expanding chamber is left free to operate by means of the spring within it. As the chamber expands, the air in the mold is expanded or rarefied through the air-vents into the air-chamber, so as to leave little or no obstruction to the ingress of the fluid metal into the mold. This method is peculiarly adapted to and is intended for the expeditious casting of small articles such as are required to be free from "blows," "strains," "flaws," &c., and when the edges, corners, or lines are required to be sharp, even, and clear, such as paper and letter seals,

ornaments, small gearing for
tory machinery, and all arti-
bility is required, and also to
of articles of hardware, &c.,
mention.

of exhausters may be used in
the expansive chamber there-
ge that the mold shall be in-
d of air by one impulse of said
e I do not use any valves in
the exhauster.

te air-passages should be made
at the highest portion of the
astings for most purposes can
ome recesses of the molds are
crevices, for the air is almost
d from the mold before the
in.

y, claim exhausting the mold
to or while running in the

melted metal, nor the use of molds having
vents arranged for the escape of confined or
compressed air; nor do I claim the substitu-
tion of a simple expansive air-chamber for an
air-pump in casting metals by atmospheric
pressure.

I claim as my invention, and desire to se-
cure by Letters Patent—

Instantaneously removing the air which nor-
dinally fills the mold into an air-tight ex-
pansive chamber through crevice-like air-
passages arranged for the purpose immedi-
ately after the open mouth of the mold is im-
mersed in the fluid metal, all as herein de-
scribed and specified, whereby the advantages
herein set forth are attained.

EZRA RIPLEY.
